(57) CLAIM

The ornamental design for a chair, as shown and described.

DESCRIPTION

FIG. 1 is a front and side perspective view of the chair, showing my new design;

FIG. 2 is a side elevational view, the side opposite to that shown in FIG. 2 being the mirror image thereof;

FIG. 3 is a front elevational view thereof; and,

FIG. 4 is a rear elevational view thereof.

1 Claim, 4 Drawing Sheets
